(57) CLAIM

The ornamental design for a pressure detecting sensor, as
shown.

DESCRIPTION

FIG. 1 is a top, front and right side perspective view of a
pressure detecting sensor showing our new design;

FIG. 2 is a front view thereof, the rear view being a mirror
image of the front view;

FIG. 3 is a top plan view thereof, the bottom plan view being
an identical image of the top plan view;

FIG. 4 is a left side view thereof; and,

FIG. 5 is a right side view thereof.
